[57] CLAIM

The ornamental design for a DC to AC power inverter, as shown and described.

DESCRIPTION

FIG. 1 is a front perspective view of the DC to AC power inverter showing my new design,

FIG. 2 is a rear perspective view thereof,

FIG. 3 is a front elevational view thereof,

FIG. 4 is a top plan view thereof,

FIG. 5 is a righthand side view thereof,

FIG. 6 is a rear end view thereof,

FIG. 7 is a bottom plan view thereof,

FIG. 8 is a lefthand side view thereof,

FIG. 9 is a perspective view of an alternative embodiment of a DC to AC power inverter showing my new design; and,

FIG. 10 is a front elevational view thereof.

All other views of the alternative embodiment are the same as corresponding views of the first embodiment.
